BASE FOR STOVE

John E. Chambers, Thomas Esta Phares, and Samuel Maurice Young, Shelbyville, Ind., assignors to Chambers Corporation, a corporation of Indiana

Application March 14, 1950, Serial No. 149,534

7 Claims. (Cl. 126—39)

This invention relates to a base for a stove and refers particularly to a base that may be readily positioned on the stove or removed therefrom.

The base of the present invention is in the form of an apron which closes the gap between the bottom of a stove mounted on legs and the floor, in the front and on the opposite sides. The base has a two fold purpose, to provide a neat appearance for the lower edge of a stove and to promote cleanliness in the kitchen in and around the stove. Base members that are permanently secured to the lower edge of a stove have the disadvantage that they make it extremely difficult to clean the kitchen floor under the stove. The same condition exists if the base is hard to remove or to replace, or if tools are required for either the removal or replacement of the base.

The base constructed in accordance with the present invention is independent of the stove and may be removed or replaced readily by an average housewife without tools of any kind. Because of this the housewife can undertake as part of the regular cleaning of the kitchen floor the cleaning of the floor portion beneath the stove, a chore seldom if ever done where the stove is provided with a base which is secured to the frame of the stove and hence is not readily removed. Another advantage of applicants' base is that it automatically adjusts itself to the floor level so that even if the kitchen floor is not level, the base will not leave an unsightly gap under a portion of its lower edge where it would be noticeable.

The structure by means of which the above noted advantages and other advantages of the invention are attained will be described in detail in the following specification, in conjunction with the accompanying drawings showing a preferred illustrative embodiment of the invention, in which:

Figure 1 is a perspective view of a stove to which the base has been applied, with a lower corner portion broken away to show a portion of the structure by which the base is secured to the stove;

Fig. 2 is a perspective view of the base shown in conjunction with a fragmentary portion of the stove to which the base is to be applied in dotted lines, one of the two brackets on the opposite sides of the stove to which the rear extremities of the base is to be secured being shown in full lines;

Fig. 3 is a cross sectional view, taken along the line 3—3 of Fig. 1, showing the means for securing the rear portions of the side panels of the base to the stove.

Fig. 4 is a cross sectional view, taken substantially along the line 4—4 of Fig. 1, with the rear portions of the side panels of the base shown broken away;

Fig. 5 is a view, similar to Fig. 4, showing the base just before it has been secured to the stove;

Fig. 6 is a fragmentary front elevation of the lower portion of the corner structure of the stove showing, in dotted lines, the base with its clip engaging the leg bolt of the stove; and

2

Fig. 7 is a fragmentary cross sectional view showing the front panel of the base secured to the leg bolt of the stove.

In the drawings, the reference numeral 2 indicates a stove having a plurality of leg bolts 3 supporting it in spaced relationship to the floor. The leg bolts are each provided with a rounded head 4 which rests on the floor, and a nut 5 threaded tightly against the bottom of the stove. The distance between the top of nut 5 and the rounded head of the leg bolt determines the distance between the floor and the bottom of the stove. This is the space which the base is designed to cover.

The base comprises a front panel 6 and side panels 7. Front panel 6 is provided at its upper edge with a flange 8 and at its lower edge with a flange 9 to give it sufficient rigidity. A pair of resilient clips 10 is secured to the rear surface of the front panel with each clip positioned so as to be in lateral alignment with one of the leg bolts of the stove when the base is applied to the stove. The clips may be welded to the front panel, but it is preferred to secure them by bolts 11.

Each clip 10 is made of a single strip of resilient spring steel having its central portion 12 secured to the rear surface of front panel 6. Both ends of the strip are bent at right angles at the lateral edges of central portion 12 to form arms 13 extending rearwardly from the front panel. The arms extend parallel a short distance and then merge into converging portions 14 which form a bottleneck at point 15. Rearwardly of bottleneck 15 the arms are bent outwardly and then inwardly, as indicated at 16 and 17, to define a space adapted to receive the shank of a leg bolt. Converging portions 17 are spaced apart at their rearmost end a distance slightly less than the diameter of the shank of leg bolt 3 and merge into outwardly flared wings 18. When front panel 6 is positioned in front of the stove and pushed rearwardly towards the position it occupies when applied to the stove, the outwardly flared wings enable one to readily locate the base properly relative to the legs. The wings engage the shank of leg bolt 3 and are forced outwardly until the shank of the bolt passes the restricted opening 19.

The resilience of the metal strip causes the arms of the clip to snap into their normal position with the shank of the leg bolt 3 embraced by portions 16 and 17. Opening 19 is narrow enough to prevent accidental displacement of the front panel, but wide enough to permit easy entrance of the shank of the bolt when the panel is pushed rearwardly, and easy removal of the clip from the bolt when the front panel is pulled forwardly. The distance between portions 12 and 15 is such that when the shank of bolt 3 is embraced by portions 16 and 17 of the clip the front panel is positioned under the front of the stove a short distance from the front line of the stove. This gives the lower front edge of the stove an offset appearance, as indicated at 20, Fig. 1. In connection with stoves having legs that are not suitable as an anchorage for the clips, it is possible to provide such stoves with suitable projections, and to arrange the clips to engage such projections.

When the front panel is being positioned against the front of the stove it is held with its lower edge against the floor, and the clips, when engaged with the shanks of leg bolts 3, hold the front panel with its lower edge against the floor even if the floor is off level. Since the base is entirely independent of the stove, the base will adjust itself to the surface of the floor, rather than to the front of the stove. This arrangement prevents the formation of a gap between the bottom of the front panel and the floor. If the floor slopes somewhat, so that the top and bottom edges of the panel cannot be parallel to both the floor and the bottom front edge of the stove,

the gap will be formed between the top edge of the front panel and the adjacent bottom front edge of the stove. The gap will not be noticeable in this position because it will be substantially concealed by the overhang 20.

Side panels 7 are secured to opposite ends of front panel 6 in any suitable manner, as indicated at 21, Fig. 7. The side panels are provided with top and bottom flanges 22 and 23, respectively, to provide a desired amount of rigidity for the structure. Each side panel has a clip 24 welded or otherwise secured thereto on its inner side and adjacent its rear end. The clip is offset inwardly, as indicated at 25, to form a lip 26 spaced parallel to the panel and having its free end extending towards the rear of the end panel.

A bracket 27 is secured to the back 31 of the stove adjacent each lower corner by a screw 32 or similar fastening element. The bracket has a portion 28 extending beyond the lateral edge of the stove. The outer end of extension 28 is bent forwardly to form a flange 29 vertically aligned with lip 26. The inner edge of bracket 27 is provided with a rearwardly extending flange 30 which serves to stiffen the bracket.

As previously mentioned, the side panels may be secured to opposite ends of the front panel in any suitable manner. A pair of fastening elements 21, one or more on each side, is sufficient to hold the side panels secured to the front panel to form a single U-shaped unit that may be readily secured to the leg bolts, or to any other suitable projections, or removed therefrom without the use of any tools. The base is secured to the stove by aligning it with the stove at floor level and pushing it rearwardly until wings 18 of each of the clips 10 engage the shank of a leg bolt 3. Then, as the base is pushed rearwardly so that wings 18 are spread apart to permit entrance of the bolts into the restricted portions of the clips, the side panels 7 are pressed inwardly (in the direction of the arrows, Fig. 5) to cause the lips 26 to fit inside flanges 29. The interengaged elements 26 and 29 cooperate with clips 10 to hold the base in position against the stove and prevent the ends of panels 7 from swinging outwardly. Elements 26 and 29 each are of sufficient height to insure vertical alignment even if the floor is off level so that the lips 26 on opposite side panels are positioned at slightly different levels.

From the foregoing it will be seen that we have provided a base that is entirely independent of the stove and may be secured to the stove, or removed therefrom, easily and quickly by an ordinary housewife without the use of any tools. While we have described a preferred embodiment of the invention in considerable detail it will be understood that the description is intended to be illustrative, rather than restrictive, as many details may be modified without departing from the scope of the invention as defined in the appended claims. Accordingly, we do not desire to be restricted to the exact structure of the illustrative embodiment disclosed.

We claim:

1. In combination with a stove having a front, a back, a pair of legs adjacent its front and a bracket adjacent each lower corner of its back, a base comprising a front 60

panel having a clip engageable with each of said legs and a pair of side panels, each of said side panels having a clip engageable with one of said brackets.

2. In combination with a stove having a back and a bracket secured adjacent each of the lower back corners of the stove, a unitary base comprising a front panel and a pair of side panels, each of said side panels having a clip engageable with one of said brackets to hold said side panels against accidental displacement.

3. In combination with a stove having a back and a bracket secured adjacent each of the lower back corners of the stove, each of said brackets having a flange extending beyond the lateral edge of said stove, a base comprising a front panel and a pair of side panels, each of said side panels having a rearwardly extending clip spaced inwardly from said panel, said clip being engageable with said flange to prevent accidental displacement of said side panels.

4. In combination with a stove having a pair of vertically adjustable leg bolts adjacent its front and a bracket secured to each lower corner of its back, a base comprising a front panel having a pair of resilient clips extending rearwardly from its rear surface, each of said clips being removably engageable with one of said legs to hold said base in engagement with said stove, and a pair of side panels each secured at its front end to said front panel and having a clip secured adjacent its rear end, each of said clips being removably engageable with one of said brackets, whereby each of said side panels is removably secured adjacent its rear end to said stove.

5. In combination with a stove having a front, a back, a pair of legs adjacent its front and a bracket adjacent each lower back corner, a unitary base comprising a front panel and a pair of rearwardly extending side panels, said front panel being removably engageable with said legs, and each of said side panels being adapted to be removably secured adjacent its rear end to one of said brackets.

6. In combination with a stove having a front, a back, a pair of legs adjacent its front and a bracket projecting laterally from each lower back corner, a unitary base comprising a front panel and a pair of rearwardly extending side panels, a pair of resilient clips extending rearwardly from said front panel, said clips being laterally aligned with said legs, and each of said side panels being engageable adjacent its rear end with one of said brackets.

7. In combination with a stove having brackets secured thereto, a base comprising a front panel and a pair of side panels, said front panel having a plurality of clips engageable with part of the stove, and said side panels each having a clip extending inwardly from its inner surface and engageable with one of said brackets.
